UNITED STATES PATENT OFFICE

119,118

DESIGN FOR A TEXTILE FABRIC

Benjamin Kleinman, New York, N. Y.

Application January 22, 1940, Serial No. 89,621

Term of patent 3½ years

To all whom it may concern:

Be it known that I, Benjamin Kleinman, a citizen of the United States, residing in New York city, in the county of New York and State of New York, have invented a new, original, and ornamental Design for a Textile Fabric, of which the following is a specification, reference being had to the accompanying drawing, forming part thereof.

The figure is a plan view of a textile fabric showing my design.

I claim:

The ornamental design for a textile fabric, substantially as shown.

BENJAMIN KLEINMAN.
